United States Patent Office.

JOHN RICHARDS, OF WASHINGTON, DISTRICT OF COLUMBIA.

Letters Patent No. 66,739, dated July 16, 1867.

IMPROVED IMPLEMENT FOR WAGONERS.

The Schedule referred to in these Letters Patent and making part of the same.

TO ALL WHOM IT MAY CONCERN:

Be it known that I, JOHN RICHARDS, of the city of Washington, District of Columbia, have invented a "Hatchet, Hammer, and Wrench, combined with an adjustable Screw-Driven and Auger;" and I do hereby declare the following to be an exact description thereof, reference being had to the accompanying drawings, and to the letters of reference marked thereon, making a part of this specification, in which—

Figure 1 represents the whole combination of the devices carried by a wagoner as the key-bolt of an axle or double-tree.

Figure 2, a top view.

The nature of my invention consists in the construction and combination of the devices, and the object is to keep the devices or tools together, so that either one may be used when required, and be portable and convenient for use.

A represents the hatchet, B the hammer, and C C notches of various sizes to answer as a wrench. The handle D is of metal, solid with the hatchet, and provided at its end E with a screw-thread, F, and the auger or gimlet G operating on the screw. The screw-driver H fits on the handle against a shoulder. It is a circular plate with three projections J, two of which have screw-driver edges, and the third a small wrench.

A farmer or wagoner may always have these tools with him in travelling, to use in case of accident, by using the handle as a bolt to his axle or double-tree K; the screw-driver plate H answering the purpose of a washer, and the auger G as a nut or fastening below to prevent the hatchet from jumping out of its place. The point E of the handle is intended to bore holes in the harness of the horses, when necessary, and not deface or spoil the harness.

What I claim as my invention, and desire to secure by Letters Patent, is—

The improved implement for wagoners, constructed and arranged substantially as herein described and for the purposes set forth.

JOHN RICHARDS.
